UNITED STATES PATENT OFFICE

REINHOLD B. MARSCHKE, OF ST. PAUL, MINNESOTA

COLLAPSIBLE CONCEALING LADDER

Application filed February 21, 1929. Serial No. 341,661.

My invention relates to a new and useful improvement in collapsible and disappearing ladders, the primary object of which is to provide a ladder with hanger means so that the ladder may be hung concealed in the ceiling of a room or hallway, and may be readily let down to extend to the floor below.

My invention includes hanger means to allow the easy and efficient operation of the ladder, to hold it in place concealed in the casing provided for it when not in use, and to allow it to swing easily down into operative position when there is a slight pull upon the depending member arranged for that purpose.

A feature of my invention resides in the simplicity of construction and the low cost at which my collapsible ladder may be manufactured.

It is an added feature of my invention to provide a ladder that may be collapsed into a compact form of comparatively small dimensions compared to the length of the ladder. This is accomplished by the collapsible form of my ladder and is very desirable in that it takes up but little space when installed and in that it may be easily packed for shipment.

An object of my invention is to provide adjustable spring means for balancing my ladder so that the same will fold up and pull down easily with a minimum amount of effort on the part of the operator.

These details together with other details of construction of my invention will be more clearly defined in the specification and claims.

In the drawings forming a part of this specification:

Figure 1 is a perspective view of my ladder as it would appear in operative position.

Figure 2 is a side view of my ladder before the lower section is let down into operative position.

Figure 3 is a plan view of my ladder as it would appear collapsed.

Figure 4 is a side view of Figure 3, when the ladder is folded up.

Figure 5 is a detail of a portion of my ladder.

My ladder A is formed of two portions 10 and 11 which form a single continuous ladder when in operative position, but which telescope together when not in use. The upper portion 10 is connected to a casing 12 at the point 13 by means of hinges 14. The casing 12 is located in the ceiling of a room or hallway. To add to the appearance when the ladder is folded and not in use, I have provided a sheathing or flooring member 15. This member 15 closes the opening in the casing 12 when the ladder is in inoperative position and provides a neat and finished appearance.

The upper portion 10 of my ladder is provided with rungs 16 or steps and is wider than the lower portion 11. The lower portion 11 is formed with grooves 17 extending virtually the entire length of the sides 18. This lower portion 11 is adapted to slide within the sides 19 of the upper portion 10 of my ladder, the lower edge 20 of the sides 18 of the lower portion 11 sliding over the rungs or steps 16. Small pegs 21 located near the lower end 22 of the upper portion 10 of my ladder are adapted to project inwardly from the sides 19 and to slide in the grooves 17. This groove 17 is curved near the upper end of the lower portion 11 of the ladder A to allow the sides 18 of the lower portion 11 of my ladder to be positioned virtually in line with the sides 19 of the upper portion 10 of my ladder, thus putting the rungs 23 of the lower portion of the ladder in line with the rungs 16 on the upper portion to form a continuous ladder or stairway.

To facilitate the raising and lowering of my ladder I have provided spring hanger means B. Two arms 24 and 25 pivotally connect the ladder at the point 26 to the casing at the point 27. These arms 24 and 25 are

pivoted at the point 28. Coil springs 29 or other suitable spring means are connected at one end to the upper arms 24 at 30. The other end of the springs 29 is connected to the casing 12 at 31. These springs 29 aid in the action of the arms 24 and 25 and balance the weight of the ladder so as to permit the ladder A to go back into closed position without any exertion on the part of the operator after the ladder has been started in motion.

When it is desired to use my ladder, the ladder is opened by a slight pull on the depending member 32 arranged for that purpose. The ladder is then in the position shown in Figure 2, with the lower portion 11 partially within the sides 19 of the upper portion 10, and is held in that position by the catch 33. The lower portion 11 is then released by turning the catch 33 and allowing the lower portion 11 to slide down into position, the pegs 21 sliding in the grooves 17 to guide the movement. To close the ladder into its normal position the process is reversed. The lower portion 11 is slid on to the upper portion 10 of my ladder, the catch 33 is turned to keep the lower portion 11 in this position, and the ladder A is given a slight upward start. This allows the arms 24 and 25 to start folding together and the spring 29 acts upon these arms to continue the folding process and to bring the ladder into closed position.

To allow for the proper adjustment of the spring 29 and to cause the arms 24 and 25 to act easily, the point 31 is situated at the proper point on the casing 12 to give correct tension to the spring 29. This may be adjusted in each particular case and may be moved from time to time should it prove necessary.

Thus I have provided a ladder which may be collapsed into compact form so that it will take up very little room. It is a valuable addition to a small house or bungalow where there is not much space for stairs, where a simple and inexpensive means of reaching an upper floor or attic is desired. It is also a feature that while my ladder is very small and compact when in folded position, it is not too steep for easy and safe ascension or descent when in operative position, and I believe I have filled a long felt want in providing this convenience.

In accordance with the patent statutes I have described the principles and particular features of my invention together with the best embodiment thereof in the drawings, and while these illustrations show a particular form and construction, I desire to have it understood that these are only illustrative of a means of carrying out my invention and that the same can be applied to other uses than those above set forth within the scope of the following claims:

I claim:

1. A collapsible concealing ladder includ-
65 ing, a ceiling closure member, a ladder sec-

tion rigidly supported on the inner surface of said closure member, a slidable ladder section having longitudinal grooves in the sides thereof, supporting pins operable in said grooves and carried by said first ladder section to allow said slidable section to slide in said first ladder section, side folding brackets for said first section and closure member, and coil spring members extending along said bracket members adapted to urge the folding of said bracket members and balance the weight of said sections and closure member when said sections are folded on the inner surface of said closure member.

2. A collapsible concealing ladder for buildings including, a closure, a frame for supporting said closure in a manner to permit one side to hinge from said frame to permit said closure to be opened by pulling down on the same, a ladder section rigidly carried on the inner surface of said closure member, foldable brackets extending from said supporting frame to the sides of said ladder section, spring means for urging the folding of said brackets and balancing said ladder, and an extension ladder section slidably supported by said first section in a manner to extend therefrom when said ladder and closure are opened, said closure acting as a supporting surface for said extension ladder section when in opened position.

3. A collapsible concealing ladder adapted to extend from the ceiling of a building comprising a frame, a closure hinged to said frame, a ladder section fixed to the inside of said closure, folding bracket means for said fixed ladder section and closure, a slidable ladder section, and means for supporting said slidable section in a manner to extend in longitudinal alinement with the side rails of said fixed ladder section when extending from the free end of said closure and to lie parallel to and on top of the rungs of said fixed section when folded to permit folding of the ladder within said casing in a compact state in the ceiling of a building.

4. A ladder and closure for buildings including, a supporting frame, said closure being adapted to close the opening in said frame in the ceiling of the building and being hinged to said frame, ladder sections, one of which is rigidly supported by said closure on the inner surface thereof, folding brackets extending from the sides of said frame to the sides of said fixed ladder section, resilient means for urging the folding operation of said brackets, and means on said fixed section for supporting slidably the other section of the ladder to extend from the first section to form an extension in line with the side rails thereof when extended and said closure is opened and cam means to cause said slidable section to slide on top of said fixed ladder section and fold within said

frame in said frame opening when said closure is closed.

5. A collapsible concealing ladder for buildings including, a frame and a closure hinged thereto, ladder portions one of which is fixed to said closure and the other slidably on said fixed portion, means for supporting said slidably portion upon said fixed portion slidably, and folding bracket means for supporting said closure and ladder portions in a manner to permit the same to be collapsed and folded into said frame when said closure is closed and to extend therefrom when said closure is open, and cam means for placing said slidably portion above said fixed portion.
